UNITED STATES PATENT OFFICE.

BERNHARD SÜSSIS, OF NEW YORK, N. Y., ASSIGNOR OF ONE-HALF TO LOUIS CRYSTAL, OF NEWARK, NEW JERSEY.

FIRE-ESCAPE.

1,103,850.

Specification of Letters Patent. Patented July 14, 1914.

Application filed March 26, 1913. Serial No. 757,010.

To all whom it may concern:

Be it known that I, BERNHARD SÜSSIS, a subject of the Czar of Russia, residing at New York city, in the county of New York and State of New York, have invented new and useful Improvements in Fire-Escapes, of which the following is a specification.

This invention relates to fire escapes and particularly to those adapted for arrangement on the exterior of buildings and has for its general object to improve the construction of a fire escape, so that it may serve as a car for readily and conveniently emptying a building of its occupants in a minimum of time. And to this end the invention consists in certain combination and arrangements of parts hereinafter more fully described and pointed out in the appended claim.

Other objects will appear and be better understood from that embodiment of my invention of which the following is a specification, reference being had to the accompanying drawings forming part hereof, in which:

Figure 1 is a front elevation of a building showing my invention applied thereto. Fig. 2 is a top plan view thereof with the housing removed. Fig. 3 is a cross sectional view taken on the line 3—3 of Fig. 2. Fig. 4 is a cross sectional view taken on the line 4—4 of Fig. 2 and showing the car at its lowest position. Fig. 5 is a detail view of a portion of one of the rack bars. Fig. 6 is a horizontal sectional view taken on the line 6—6 of Fig. 4. Fig. 7 is a horizontal sectional view showing a modified form of connecting the car to the end of a building.

My invention involves a thorough and radical departure from the former types of fire escapes now in use. Heretofore, fire escapes have been permanently secured to the outsides of buildings and access to the same has been limited to the windows located adjacent thereto. The efficiency in time of need of this type of fire escape has often for various reasons, proven unsatisfactory.

My invention is designed to overcome the various defects of fire escapes now in use and to improve the outer appearance of buildings; and to these ends my invention consists of providing the outer wall of a building 1 with an upright pair of rack bars 2 over which is adapted to travel a car 3,

which, when in its upper or normal position, is adapted to serve as a cornice.

The car extends the entire width of the building, is formed on its outer or exposed face with the usual ornamental design 60 formed in cornices and is designed to be raised and lowered over all the windows on the various floors by means of a suitable hoisting and lowering mechanism connected to the building and to the car. The car consists of two hingedly connected sections 4 and 5, the section 4 of which is provided with a platform 6 on which is mounted an electric controller 7 for regulating the speed and upward and downward movement of 70 the car when in use. The section 5 is formed with the steps 8 and is held in its normal upper position as (shown in Figs. 1 and 3) by means of the side chains 9 engaging side or guard rails 10 mounted on the sides of 75 the section 4. In this position the step section acts as a side guard for the car when the same is in use; that is when the car is carrying a load of people while descending. After the car has reached the ground or its 80 lowermost position, the chains are released from engagement with the side rails, thereby allowing the step section to swing to its lower position (as shown in Fig. 4) whereby the steps may be used by the occupants 85 of the car to descend to the ground.

Located within the bearing plates 11 secured to each end of the body of the car is a drive shaft 12 on the ends of which are keyed the pinions 13 for engagement with 90 the rack bars 2 for hoisting and lowering the car when in use. The inner ends of the bearing plates are provided with the hook portions 14 which are arranged to slide in the grooves 15 formed in the side walls of 95 the rack bars, for guiding the car in its upward and downward descent and for preventing the same from swinging away from the building.

A hoisting and lowering drum 16 is keyed 100 to the shaft 12 at the central portion of the car, and over which is coiled the lower ends of a pair of cables 17, the upper ends of which are coiled around the drums 18 and 19 mounted on a shaft 20 held in suitable 105 bearings secured to the top of the building. A pulley 21 mounted on the shaft 20 between the drums 18 and 19, is adapted to be operated through a driving cable 22 from an electric motor 23 for winding and un- 110

winding the drums when the device is in use.

An additional hoisting and lowering mechanism for the operation of the device is also employed. This mechanism comprises drums 24 and 25 mounted on each end of the shaft 25', and held in suitable bearings secured to the top of the building. Around these drums are coiled the cables 26 and 27, each of which is adapted to be wound and unwound upon its drum when the car is in use. These cables operate simultaneously and in conjunction with the cables 17 during the raising and lowering 10 of the car. From the inner ends of the drums each of the cables pass backward over a sheave 28 then forward over a sheave 29 located on the top edge of the building, then around sheaves 30, 31 and 32 located 15 on the car, then upward around a sheave 33 also located on the top of the building and then backward around a sheave 34 to the other or outer end of the drum, as clearly shown in Fig. 2. A pulley 35 mounted 20 on the central portion of the shaft 25', is also adapted to be operated through a driving cable 36 from the electric motor 23 for winding and unwinding the drums 24 and 25 when the device is in use.

30 The car is also designed to carry a pipe 37 to which may be connected at suitable points, the usual fire hose when the same is desired to be used for more advantageously fighting a fire.

35 In the modification shown in Fig. 7, the end of the car is shown provided with an extended and rounded end portion 40 which is adapted to embrace the corner of a building

and to be guided within the grooved rack bar 41, as shown. In this form the rack bar 40 is provided with angularly disposed teeth which are engaged by pinions 42 and 43 connected by means of the bevel gears 44 and 45, the gear 45 and pinion 43 being mounted on the drive shaft 46.

45 A suitable housing (not shown in the drawings) may be provided for protecting the operating elements of my improved device against the various weather conditions.

50 It is obvious that those skilled in the art may vary the details of construction and arrangements of parts without departing from the spirit of my invention and therefore I do not wish to be limited to such features except as may be required by the claim.

55 What is claimed as new is:

A fire escape adapted to be used in combination with a building comprising bars arranged vertically along the building each having angularly disposed sides, two of the 60 adjacent said sides being provided with longitudinally disposed grooves and two of the adjacent sides being provided with teeth, a car mounted for movement along the bars and having hook portions which are 65 slidably received in the grooves, gear wheels journaled upon the car and operatively connected together and meshing with the teeth upon the bars, and means mounted upon the building for rotating the gear wheels.

70 In testimony whereof I affix my signature in presence of two witnesses.

BERNHARD SÜSSIS.

Witnesses:

LOUIS CHRYSTAL,
GEO. A. BYRNE.
